UNITED STATES PATENT OFFICE

2,425,026

BURNER WITH DETACHABLE GENERATOR CHAMBER

James L. Breese, Santa Fe, N. Mex., assignor to
Oil Devices, Santa Fe, N. Mex., a limited partnership of Illinois

Application January 13, 1944, Serial No. 518,048

3 Claims. (Cl. 158—91)

1

My invention relates to an improvement in burners and has for one purpose to provide an improved burner for burning liquid fuels.

Another purpose is to provide improved means for regulating the flow of liquid fuels to a burner.

Another purpose is to provide an improved means for preventing flow from a fuel tank when the closure of the fuel tank has been removed.

Another purpose is to provide an improved generator or liquid fuel vaporizing chamber for a liquid fuel burner.

Another purpose is to provide a removable generator or liquid fuel vaporizing chamber for a liquid fuel burner.

Other purposes will appear from time to time throughout the specification.

My invention is illustrated more or less diagrammatically in the accompanying drawings, wherein

Figure 1 is a vertical section;

Figure 2 is a partial plan view with parts broken away; and

Figure 3 is a section along the line 3—3 of Figure 1.

Like parts are indicated by like characters throughout the specification and drawings.

Referring to the drawings, 1 generally indicates a burner pot herein shown as having a plurality of primary air inlet apertures 2, spaced circumferentially thereabout and located at various distances from the end of the pot. The pot is shown as having a closed bottom or end 3, which may be continuous with the circumferential side wall of the pot. The side wall is also provided with a plurality of secondary air inlets 4, shown as arranged in a single circumferential row adjacent the open end of the pot. The secondary air inlet apertures 4 are shown as tilted whereby jets of air are directed inwardly and toward the open end of the pot. The pot has a terminal flange 5 extending outwardly from its open end. 6 is an outer surrounding skirt or circumferential outer wall. It may be secured to the flange by any suitable screws or securing means 7. 8 is a centrally apertured flame ring.

9 indicates generally a liquid fuel vaporizing chamber having a top cover or closure 10, which is welded as at 13 to the burner pot 1. The cover is apertured as at 11 in line with an aperture 12 in the circumferential side wall of the pot 1. 14 is any suitable clamp, the ends 15 of which are supported upon the cover 10 to provide a closed loop surrounding the vaporizing chamber 9. 16 is any suitable screw passing through an abutment portion 17 of the clamp 14 and

2

adapted to be manually manipulated by the thumb portion 18, to direct pressure against the bottom of the vaporizing chamber 9 and to hold it removably in position.

19 is an air inlet tube extending downwardly through the top 10 of the vaporizing chamber 9. It is provided with a plurality of vertical slots 20 which extend substantially below the level of the liquid in the chamber 9. 21 is an inner air inlet tube nested with the tube 19 and rotatable in relation thereto. It is provided with vertical slots or apertures 22, which may be moved into or out of register with the apertures or slots 20 by rotation of the inner tube 21. The inner tube 21 may be rotated by the pin 23 which also serves as a means for supporting the inner tube 21 in proper position. It will be understood that the air supply flowing inwardly through the tube 21 and through the apertures 20 and 22 may be varied from a fully open to a fully shut position by rotating the tube 21, which constitutes a readily operable means for varying the air supply to the interior of the vaporizing chamber 9.

A supply of liquid fuel may be maintained in 25 the fuel tank 30 which is connected by a fuel pipe 31 with the interior of the vaporizing chamber 9. 32 indicates a valve block or body shown as located within the tank 30 and having a bore 33 and a larger bore 34 in which is positioned a ball 35 normally urged by the spring 36 into position to shut the passage 33. The spring is positioned within and controlled by the screw threaded hollow plug 37 which is screw threaded into the bore 34.

38 is a closure cap for the tank 30 and is shown as provided with a valve control stem 39. The parts are so proportioned that when the cap 38 is closed, the pin 39 engages the ball 35 and forces it into the open position in which it is shown in 40 Figure 1. Liquid fuel then flowing past the ball through the inlet passage 40, to the bore 33 and thence to the pipe 31.

It will be understood that when the cap 38 is open to refill the fuel tank, any flow of fuel along 45 the fuel pipe 31 is temporarily inhibited by the action of the spring 36 against the ball 35. When the cap 38 is again replaced, the pin 39 pushes the ball 35 into inoperative position and fuel may flow along the bore 33 and the pipe 31. If desired, the parts may be so proportioned as shown in Figure 1, that the ball 35 may be freed for movement to the closed position by slightly rotating the cap 38.

In the operation of the heater, fuel vapor is 55 generated in the chamber 9 by local combustion

at or above the surface of the fuel **X**, in that chamber. The supply of air necessary to maintain this initial vaporizing combustion is provided through the air inlet **21**. The rate of flow is governed by rotation of the tube **21** which is effective to vary the relationship between the slots **20** and **22**. Thus the tube **21**, in connection with the outer tube **19**, provides a shuttered, adjustable flow, air control member. The vaporized liquid fuel, preferably with some excess supply of air, flows through the aperture **12** into the interior of the pot **1**. It there receives a primary air supply through the primary air inlets **2**. This mixture then flows through the mouth or open end of the pot and receives its final air supply through the secondary air inlets **4**. The final mixture is burned at or near the flame ring **8**, the flame extending to the right of the flame ring **8**, referring to the position of the parts as shown in Figure 1.

It will be understood that it is immaterial whether the axis of the pot is vertical or horizontal but the horizontal arrangement is practical and efficient and provides an element which can very easily be secured to the side or front of a stove or heater, in such fashion that the flame projects into the fire box or combustion chamber of the stove or heater.

The liquid fuel vaporizing chamber **9** may be made unitary or may be permanently secured to the pot structure but under some circumstances I find it advantageous to make it removable, as shown herein.

It will be realized that whereas I have shown and described an operative device, still many changes may be made in the size, shape, arrangement and number of parts without departing materially from the spirit of my invention. I wish, therefore, that my showing be taken as in a large sense diagrammatic.

I claim:

1. In a liquid fuel burner, a horizontally axised burner pot having a circumferential side wall, a closed end wall and an open end, said circumferential side wall having therein a plurality of primary air inlet apertures spaced circumferentially thereabout and located at various distances from the ends of the pot, secondary air inlet means located adjacent the open end of the pot, said circumferential side wall having an aperture located adjacent the closed end wall of the pot, means forming a liquid fuel vaporizing chamber below said pot, the interior of the liquid fuel vaporizing chamber being in communication with the interior of said pot through said aperture, means for supplying to the interior of said vaporizing chamber a variable supply of air and means for supplying liquid fuel to the interior of said vaporizing chamber.

2. In a liquid fuel burner, a horizontally axised burner pot having a circumferential side wall,

a closed end wall and an open end, said circumferential side wall having therein a plurality of primary air inlet apertures spaced circumferentially thereabout and located at various distances from the ends of the pot, secondary air inlet means located adjacent the open end of the pot, means forming a liquid fuel vaporizing chamber underlying one end of the pot, said circumferential side wall having an aperture located adjacent the closed end wall of the pot, the interior of the liquid fuel vaporizing chamber being in communication with the interior of said pot through said aperture, means for supplying to the interior of said vaporizing chamber a variable supply of air

10 and means for supplying liquid fuel to the interior of said vaporizing chamber including a fuel tank and a liquid fuel supply duct extending from said tank and downwardly into said vaporizing chamber and having an open end located below the level of the liquid fuel in said vaporizing chamber.

15 3. In a liquid fuel burner, a horizontally axised burner pot having a circumferential side wall, a closed end wall and an open end, said circumferential side wall having therein a plurality of primary air inlet apertures spaced circumferentially thereabout and located at various distances from the ends of the pot, secondary air inlet means located adjacent the open end of the pot, means forming a liquid fuel vaporizing chamber underlying the pot, and means for supplying a liquid fuel, for vaporization, thereto, said circumferential side wall having an aperture located adjacent the closed end wall of the pot, the interior of the liquid fuel vaporizing chamber being in communication with the interior of said pot through said aperture, and means for supplying to the interior of said vaporizing chamber a variable supply of air.

40 JAMES L. BREESE.
